UNITED STATES PATENT OFFICE.

MARCEL GENDRON, OF PARIS, FRANCE.

DISTRIBUTING DEVICE FOR AUTOMATIC COMPRESSED-AIR STARTING APPARATUS FOR INTERNAL-COMBUSTION ENGINES.

1,103,001.

Specification of Letters Patent.

Patented July 7, 1914.

Application filed November 27, 1912. Serial No. 733,875.

To all whom it may concern:

Be it known that I, MARCEL GENDRON, a citizen of the Republic of France, and a resident of 22 Rue Torricelli, Paris, France, have invented a certain new and useful Improved Distributing Device for Automatic Compressed-Air Starting Apparatus for Internal-Combustion Engines, of which the following is a specification.

- 10 The present invention has reference to a distributing device for automatically starting internal combustion engines by compressed air. This distributing device comprises pistons operated by a cam shaft 15 which receives its movement from the engine shaft and these distributing pistons are automatically disengaged from the action of the cam shaft when the supply of compressed air is cut off. Consequently during 20 the normal running of the engine the only resistance introduced by the starting device arises from the rotation of the cam shaft. This resistance can be made negligible by the employment of ball bearings. 25 The annexed drawing shows by way of example one method of carrying out the invention when applied to a four cylinder motor.

Figure 1 is a longitudinal section of the 30 device. Fig. 2 is a corresponding transverse view partly in section on the line 2-2 of Fig. 1. Fig. 3 is a vertical section of the controlling apparatus of the starting device. The Fig. 4 is a longitudinal section through 35 a modified form of the distributing apparatus.

The apparatus comprises four distributing pistons a movable in cylinders b which latter communicate both with the compressed air reservoir by means of the passages c and with the engine cylinders by means of passages d which may be furnished with stop valves. The pistons a are operated by rods a^1 provided at their lower 45 ends with rollers a^2 which ride on the cams e^1 on the shaft e . The springs a^3 tend to keep the rollers a^2 always on the surface of the cams e^1 . The shaft e is mounted in ball bearings e^2 and receives its motion from the 50 principal engine shaft. The cams e^1 are arranged in such a manner that the ports a^4 in the distributing pistons a make a connection between the compressed air reservoir and that cylinder in which an expansion has 55 just taken place.

A longitudinally movable bar f traverses openings a^5 cut in the rods a^1 of the distributing pistons. The bar f terminates at one end in a piston f^1 which is movable in a cylinder g which latter can be put into connection with the reservoir of compressed air by means of the passage g^1 . At the other end the bar f terminates in a plate f^2 abutting against a spring h which tends to move it in the direction of the arrow X . Lastly 60 the bar f carries inclined projections f^3 which can enter the openings a^5 in the rods a^1 to effect the raising of the distributing pistons a .

In order to start the engine compressed 70 air is first admitted into the cylinder g by the passage g^1 . The bar f is pushed in a direction opposite to that of the arrow X . The rollers a^2 therefore come into position over the cams e^1 and the distributing device 75 is ready to operate. Compressed air is then admitted by the passages c as far as the distributing pistons a which allow its admission to the proper cylinder.

When the engine is running the compressed air admission is stopped. The bar f is automatically displaced by the action of the spring h in the direction of the arrow X . The inclined projections f^3 enter the openings a^5 of the rods a^1 and raise the distributing pistons a which thereupon cease 80 to be in engagement with the shaft e . This latter continues to rotate but requires only a very small expenditure of energy by reason of it being mounted on ball bearings. 85 90

Fig. 3 shows by way of example one means of operating the apparatus which controls the starting device. The apparatus comprises three chambers i , j and k arranged one above the other. The chamber i communicates by a passage i^1 with the compressed air reservoir and with the chamber j by means of a valve j^1 kept in place by a spring j^2 . The stem of this valve terminates in a push stud j^3 . The chamber j is connected 95 with the cylinder g by the passage g^1 . It can communicate with the chamber k by means of a valve k^1 kept in place by a spring k^2 . The stem of the valve k^1 is placed in line with that of the valve i^1 but it is separated therefrom by a distance of a few millimeters. The chamber k communicates through the passages c with the distributing pistons. When the push stud j^3 is pressed 100 (by the foot for example) the valve j^1 is 105 110

first opened and compressed air is in consequence admitted into the cylinder g and thus puts the distributing pistons into engagement. If the pressure on the stud is continued the stem of the valve j^1 comes up against that of the valve k^1 and causes the lowering of the latter. Consequently compressed air is admitted by the passages c to the distributing pistons.

10 In the Fig. 4 the distributing pistons a are replaced by the check valves l mounted on the ends of the stems l^1 which are prolongations of the rods a^1 . The valves l are furnished on their under side with a fiber washer l^2 which comes to rest when the valve is lowered on a circular rib m^1 of the valve seat m . The valve chamber n communicates with the compressed air reservoir through the passage n^1 and with a lower chamber o through the agency of openings n^2 formed in the seat m . The seat m serves as a guide for the valve stem l^1 .

15 In the chamber o moves a stop valve p of hollowed leather mounted at the base of the stem l^1 and intended to prevent the escape of compressed air toward the casing. The chamber o communicates through the passage o^1 with the engine cylinder.

20 The rollers a^2 can be applied to the surfaces of the cams e^1 by means of springs analogous to the spring a^3 of the device above described. But these can be dispensed with as the drawing shows, the pressure of the compressed air being sufficient to keep 25 the rollers a^2 in contact with the cams e^1 .

25 All the other members of the device remain identical with those described in connection with the Figs. 1 to 3.

Having now particularly described and 30 ascertained the nature of the said invention and in what manner the same is to be performed I declare that what I claim is:—

35 1. In an explosion engine, a starting device comprising a chamber having a port adapted to be connected to an explosion cylinder, a second port adapted to be connected to a source of compressed air, a valve in said chamber controlling the flow of air from one port to the other in said chamber, a valve rod, 40 a cam shaft adapted to be constantly driven from the engine, a cam thereon against which said valve rod bears in operative position and a bar with cam shoulder movable transversely to said valve rod and engaging the same to lift and hold it out of engagement with the cam on the cam shaft, during the 45 normal operation of the engine substantially as described.

50 2. In an explosion engine, a starting device comprising a series of chambers each having a port adapted to be connected to an explosion cylinder and a second port adapted to be connected to a source of compressed air, a valve in each chamber controlling the flow of air from one port to the

other in said chamber, a valve rod for each valve, a cam shaft adapted to be constantly driven from the engine, a series of differently arranged cams thereon one for each valve rod and against which said rods bear 70 in operative position, and a bar with a series of cam shoulders one for each valve rod, said bar being movable transversely to the valve rods and engaging the latter to lift and hold the same out of engagement with their respective cams on the cam shaft, during the normal operation of the engine substantially as described.

75 3. In an explosion engine, a starting device comprising a chamber having a port adapted to be connected to an explosion cylinder, a second port adapted to be connected to a source of compressed air, a valve in said chamber controlling the flow of air from one port to the other in said chamber, a valve rod, a cam shaft adapted to be constantly driven from the engine, a cam thereon against which said valve rod bears in operative position and a bar with cam shoulder movable transversely to said valve rod and engaging the same to lift it out of engagement with the cam on the cam shaft, a piston at one end of said bar and a spring at the other end of said bar, and means in connection therewith for moving 80 said bar in opposite directions transversely of the valve rods.

85 4. In an explosion engine, a starting device comprising a chamber having a port adapted to be connected to an explosion cylinder, a second port adapted to be connected to a source of compressed air, a valve in said chamber controlling the flow of air from one port to the other in said chamber, a valve rod, a cam shaft adapted to be constantly driven from the engine, a cam thereon against which said valve rod bears in operative position and a bar with cam shoulder movable transversely to said valve rod and engaging the same to lift it out of engagement with the cam on the cam shaft, a piston on one end of said cam bar, a cylinder therefor, in combination with an operating valve device and means controlled thereby for admitting compressed air first to 90 the cylinder of the transverse bar piston and then to the chamber having a port adapted to be connected to the explosion engine.

95 5. In an explosion engine, a starting device comprising a chamber having a port adapted to be connected to an explosion cylinder, a second port adapted to be connected to a source of compressed air, a valve in said chamber controlling the flow of air from one port to the other in said chamber, a valve rod, a cam shaft adapted to be constantly driven from the engine, a cam thereon against which said valve rod bears in operative position and a bar with cam shoulder movable transversely to said valve rod 100

and engaging the same to lift it out of engagement with the cam on the cam shaft, a piston on one end of said cam bar, a cylinder therefor, in combination with an operating valve device comprising communicating chambers to one of which a connection is adapted to be made from a source of compressed air, independent valves controlling the communication between the chambers on the one hand and the admission of air from the source of supply to one of said chambers on the other hand, said chambers each having a discharge port, one adapted to be connected to the cylinder of the cam bar piston

and the other to the chamber connected to the explosion cylinder, and a push device for opening said valves consecutively to admit compressed air first to the cylinder of the cam bar piston and then to the chamber connected to the explosion cylinder.

20

In testimony whereof I have signed my name to this specification, in the presence of two subscribing witnesses.
